UNITED STATES PATENT OFFICE.

JOHN M. HARGRAVE, OF CINCINNATI, OHIO.

CLAMP.

Application filed August 9, 1926. Serial No. 128,302.

This invention relates to a type of clamps known as "joiners" employing a longitudinal bar having a fixed clamping jaw at one end of the bar and a second jaw 5 slidable upon the bar, and carrying a screw parallel to the bar to cooperate with the stationary bar. The invention is particularly directed to the mechanism for bindingly holding the jaw in its adjusted position on the bar. The binding mechanism comprises 10 serrated faced blocks carried by the movable jaw relatively offset and at opposite sides or edges of the bar, to grip the edges of the bar with a slight canting of the jaw. The 15 block is recessed respectively within holders or inserts mounted with the jaws.

Therefore an object of this invention is to provide in a work clamping jaw adjustable on a longitudinal bar, a pair of toothed 20 blocks rockingly mounted and diagonally located within opposite sides of the bar engaging bore of the adjustable jaw, the blocks adapted to move toward the bar when the jaw is canted due to its outer end being 25 forced against the work and the teeth inclined after the manner of saw teeth in the direction in which the jaw tends to move along the bar under work pressure so as to effectively engage the bar edge and create a 30 positive jaw grip on the bar.

Another object of this invention is to mount springs in the jaw opposite each toothed block, the springs engaging the bar and providing a balanced mounting of the 35 jaw on the bar, each spring maintaining its respective oppositely located toothed member in engagement with the bar so that the jaw is normally sustained in any position on the bar but so balanced as to be easily movable when desired.

Another object is to provide a mounting for the gripping elements in the jaw bore, thus being in the nature of blocks secured at each side of the bore, each block grooved 45 to house those gripping elements in the same side of the bore, namely, a spring and a toothed member, and the blocks removable from the bore of the jaw without removal of the jaw from the bar, this construction being of importance in the assembly of the 50 various small elements which would otherwise be extremely difficult to place in the jaw bore.

Another object is to provide a curved base 55 to the grooves which contain the toothed members, so that these members are allowed

to rock thereon and adjust themselves, as the jaw is canted, for permitting all the teeth of the members to engage the bar with equal effect.

Further objects and certain advantages will be more fully set forth in the accompanying drawings forming a part of this specification, in which:

Figure 1 is a side view of a clamp. 65

Figure 2 is a top view of the clamp illustrating the relation of the mounting blocks to the bar.

Figure 3 is an enlarged sectional view taken on line 3-3 of Figure 2, detailing the 70 arrangement and construction of the various gripping elements in the clamp jaw.

Figure 4 is a perspective view of a mounting block removed from the jaw.

Figure 5 is a perspective view of a 75 toothed element removed from the mounting block.

Referring to the drawings the clamp comprises a longitudinal rectangular bar 1 having a fixed jaw 2 secured at one end and an 80 adjustable jaw 3 slidable longitudinally of the bar in relation to the fixed jaw. The fixed jaw 2 is riveted to the bar 1 and has a 85 faced portion 4 on the side toward the adjustable jaw and against which the work is set.

The adjustable jaw 3 carries a screw 5 threaded through a projecting end 6 of the jaw 3, the screw being parallel with the longitudinal bar. A wing shaped handle 7 90 is provided at one end of the screw and a flat head 8 is pivoted to the other end of the screw as a work engaging member. The flat head 8 is secured to the screw end by a ball and socket joint so that the head may 95 adjust itself to any irregularities in the work when the work is clamped between said head and the lower jaw.

The longitudinal bar 1 is made in any length and has a rivet 9 in its outer end for 100 preventing the removal of the adjustable clamp jaw.

The rectangular bore 10 of the jaw through which the bar extends is made of greater width than the bar and mounting 105 blocks 11 are secured within this bore at each side thereof. These blocks 11 carry the bar engaging elements, engaging the opposite edges of the rectangular bar.

Pins 12 pass through the jaw and mounting blocks and serve to maintain the blocks in the jaw bore while at the same time they

are easily driven out and the blocks removed for replacing any worn out parts in blocks.

Each mounting block has two crosswise grooves as at 13, 14, each serving to house 5 respectively springs 15 and a toothed block 16. The two mounting blocks although formed identical are put in the bore in opposite directions so that the toothed blocks 16 are diagonally related and the springs are 10 positioned in the same way (see Figure 3). The bore of the jaw is of sufficient width that when the mounting blocks are inserted and the bar aligned in the bore there is a slight clearance at each side of the bar between the bar edge and mounting blocks. 15

A toothed block 16, described in detail, is rectangular and has one side toothed as at 17 after the fashion of saw teeth. Shoulders 18 are formed at each end of the toothed 20 surface and these shoulders are overhung by projections 19 on the outer end edges of the grooves 14 for loosely maintaining the toothed members in the mounting blocks.

The springs used, are formed of flat metal 25 turned upon itself and as placed in the groove they act outwardly from the base of the groove containing them against the bar edge. The mounting blocks are of the same thickness as the bar and the same is true of 30 the various elements, so that the entire bar edge thickness is engaged.

Bringing the screw down upon the work 35 cants the adjustable jaw slightly and as a result the toothed members may be said to swing in a circle. This action causes the toothed members to be forced against the bar edge with the result that they dig in slightly and thereby positively grip the bar. The gripping action of the toothed members 40 is aided by the outward curvature of the toothed block groove base 20. Due to this bulging curvature being engaged by the flat base of the toothed blocks and to the fact that the blocks are loose in the groove 45 the blocks are permitted to rock. They automatically adjust themselves to the movement of the jaw and all the teeth engage the bar with equal effect. The teeth are inclined in the direction in which they tend 50 to move on the bar under load so that they "bite" into the bar.

It is readily apparent that this positive 55 jaw grip produced by the pivotal movement of the toothed blocks in their grooves is important since the tendency of the jaw is not only to cant under load but to slide down the bar. When the jaw is not in clamping service, the springs tend to align the jaw bore in relation to the bar, and since there 60 is a spring opposite each toothed member the jaw is balanced and the toothed members are held against the bar edge sufficiently to hold the jaw in set position. However, the easy movement of the jaw, when 65 not in service, is not interfered with since

the spring tension is the factor governing the movement of the jaw and they are made to resist only the movement of the jaw resulting from its own weight or other light forces. Movement of the jaw is further 70 eased by canting the bar in an opposite direction to the cant created by pressure in the work, this disengaging the toothed members from the bar edge.

The mounting blocks aid in assembly 75 since it is not necessary to remove the jaw from the bar to replace the various members. The members are placed in the mounting blocks and the unit is then slid into the bore at the side of the bar and the pin 80 set in place. These adjustable jaw features are for use on any style bar and where it is inconvenient or impossible to remove the jaws from the bar due to the shape or position of the bar, the feature of assembly is 85 of especial importance.

In the smaller size clamps it is only necessary to have the gripping elements at one side of the bar, so that only one insert is 90 used, that is, a mounting block carrying a toothed block and spring. Also it is to be noted that the invention relates to the features for positively engaging the jaw on the bar so that it is of no importance whether the jaw moves in relation to a fixed jaw or 95 another adjustable jaw.

Having described my invention, I claim:

1. In a clamp, a longitudinal bar, an adjustable work engaging jaw having an aperture therein through which said bar extends, mounting blocks secured in said aperture at opposite edges of said bar, toothed elements and springs mounted in recesses formed by grooves in said blocks and the side walls of the jaw, the toothed 100 elements diagonally located so as to grip the bar when the jaw is canted due to pressure against the work and the springs located opposite each toothed member so as to normally maintain the teeth against the bar 105 when the jaw is in set position and not engaging the work.

2. In a clamp, a longitudinal bar, an adjustable work engaging jaw having an aperture therein through which said bar loosely extends, toothed members and springs, mounting blocks carrying said toothed members and springs in respective grooves, each block with its various elements being identical in structure but secured 115 within the aperture at each edge of the bar in reverse manner so that the toothed members are diagonally related, and a spring opposite each toothed member for normally maintaining the teeth against the bar edge. 120

3. In combination with a longitudinal bar and an adjustable jaw apertured to receive said bar and slidably thereon, a friction creating unit, comprising, a mounting block secured within the aperture at one edge of 130

the bar, a toothed member loosely seated in said mounting block and having its teeth disposed against the bar edge, a spring mounted within the mounting block and normally maintaining the toothed member in engagement with the bar, and said teeth so positioned as to be positively engaged against the bar when the jaw is canted due to pressure at its outer or work engaging end.

4. In a clamp, a longitudinal bar, an adjustable jaw apertured to receive said bar and slideable thereon, mounting blocks secured within the aperture at opposite edges of the bar, toothed members loosely seated in slots in said mounting block at each edge of said bar, the base of said slots being outwardly curved to allow the toothed members to pivot thereon whereby all the teeth of

the members positively engage the bar edge when the jaw is canted due to pressure 20 against the work.

5. In a device of the class described, a longitudinal clamp bar, an adjustable work engaging jaw apertured to loosely engage over said bar, mounting blocks removably secured within the aperture adjacent each edge of said bar, friction elements seated within each mounting block and diagonally related, whereby when the jaw is canted due to work engaging pressures on its outer end 30 the friction elements are drawn against and grip the respective bar edges.

In witness whereof, I hereunto subscribe my name.

JOHN M. HARGRAVE.
